Primary Examiner—Lucy Lieberman*Attorney, Agent, or Firm*—Finnegan, Henderson, Farabow, Garrett & Dunner**[57] CLAIM**

The ornamental design for a bottle, as shown and described.

DESCRIPTION

FIG. 1 is a front elevational view of a bottle embodying our design, wherein the bottle is transparent;

FIG. 2 is a right side elevation of the bottle, the left side elevation is a mirror image thereto;

FIG. 3 is a rear elevational view thereof;

FIG. 4 is a top plan view thereof; and,

FIG. 5 is a bottom plan view thereof.

The broken lines shown in FIGS. 1, 2, 3, 4, and 5 are for purposes of showing environmental structure only and form no part of the claimed design.
